(57) **ABSTRACT**A new and distinct cultivar of *hydrangea* plant named 'JON01' characterized by its distinctive color of flowers.

1 Drawing Sheet

1

BACKGROUND OF THE PLANT

The present invention relates to a new and distinct cultivar of *Hydrangea*, botanically known as *Hydrangea L. macrophylla* and further known by the varietal name 'JON01'. The plant is used primarily as an ornamental. The variety 'JON01' has been asexually reproduced by cuttings. The novel flower color was consistent through several generations, and plants remain true to type after multiple generations through asexual reproduction via cuttings. The new variety is a sport mutation of the variety 'Taube', discovered in the summer of 2001 by the breeder Jos de Jong in the breeder's nursery, Gebr. De Jong Handelskwekerijen BV in Boskoop, The Netherlands. The parental cultivar is sold under the Breeder's reference name "Taube."

SUMMARY OF THE INVENTION

The following traits have been repeatedly observed and are determined to be among the unique characteristics of 'JON01'. These characteristics distinguish 'JON01' as a new and distinct cultivar:

1. Different color of flowers, with the comparator (Taube) being dark pink to rosy-pink and this variety being dark rosy-red.

Plants of the cultivar 'JON01' have not been observed under all possible environmental and cultural conditions. The phenotype may vary somewhat with variations in environment such as temperature, light intensity, length of day, irrigation amount and frequency, and/or fertilizer rate without, however, any variance in genotype.

BRIEF DESCRIPTION OF THE DRAWINGS

The invention is depicted in the accompanying colored photographs in which:

FIG. 1 shows a mature potted plant of the new variety;

2

The photograph depicts the overall appearance of the new *hydrangea* showing the colors as true as it is reasonably possible to obtain in colored reproductions of this type. Colors in the photographs may differ slightly from the color values cited in the Detailed Botanical Description, which more accurately describe the actual colors.

DETAILED BOTANICAL DESCRIPTION OF THE NEW PLANT

The following detailed description sets forth characteristics of the new cultivar.

15	Botanical Name	<i>Hydrangea L. macrophylla</i>
	Varietal Name	'JON01'
	Parentage:	Mutation of "Taube"
	Asexual Propagation	Vegetatively by cuttings
	Inflorescence:	
20	Color midzone	59B/60A (red-purple group);
	upper surface -	RHS 1995
	Fertile Flowers	star-shaped, diameter 7 mm, 4-6 petals; petal arrangement separated, color violet (RHS 85B, 1995) and white in a stripe pattern from base to apex, shape narrow cross section deep concave; pedicel length 2.2 mm, color pink
25		round-shaped, diameter 50 mm, 4-6 petals, upper profile flat, lower profile slight concave; petal arrangement touching, color of upper side purplish red (RHS 71B, 1995), color of lower side purplish red (RHS 72D, 1995), shape rounded, basal spot absent; pedicel length 20 mm, color pink (RHS 72D, 1995)
	Sterile Flowers	
30		

-continued

Development:

Resistance to Disease - Similar to other *H. macrophylla* varieties; examined plants show no signs of pest or disease resistance or tolerance than other *hydrangea macrophylla*

Age and Growing Conditions six first year plants raised in mulch beds, pH of 6.0, in full sun with some afternoon shade. Plants were of generally healthy appearance with some scorching and disfiguration from extremely hot conditions

Plant Size

Plant Height 300 mm
Plant Width 250 mm
Habit thick, rounded, branching arrangement irregular from leaf axil

Leaf Characteristics

Length 110-130 mm
Width 82-90 mm
Vein pattern prominent inset, cross section convex, undulation of margin slight
Color Green upper side (RHS 137A, 1995), green lower side (RHS 137B, 1995), veins green (RHS 144B, 1995).

Petioles

Texture Smooth
Color Green (RHS 144B, 1995)
Length 13-18 mm

-continued

Stem

Width 5-8 mm
Texture Smooth
Color Green (RHS 144C, 1995), with some small burgundy/brown dots

Bud

Shape Round
Color striped violet (RHS 85B, 1995) and white

Stamens

Number of anthers seven
Color of pollen orange
Length 1 mm

Pistil

Number of pistils three
Color Yellow
Fruit no fruit produced
Fragrance very weak to absent, leaf fragrance weak to absent

GENERAL CHARACTERISTICS

‘JON01’ is a mutation of the taube and differs from taube by the color of the flowers, with the comparator being dark pink to rosy pink and the present invention characterized by flowers being dark rosy-red.

What is claimed is:

1. A new and distinct variety of *hydrangea* plant, substantially as shown and described.
